UNITED STATES PATENT OFFICE.

BENJAMIN WOLHAUPTER, OF CHICAGO, ILLINOIS.

COMPROMISE RAIL-JOINT.

SPECIFICATION forming part of Letters Patent No. 790,608, dated May 23, 1905.

Application filed March 7, 1905. Serial No. 248,828.

To all whom it may concern:

Be it known that I, BENJAMIN WOLHAUPTER, a citizen of the United States, and a resident of Chicago, in the county of Cook and State 5 of Illinois, have invented certain new and useful Improvements in Compromise Rail-Joints; and I do hereby declare that the following is a full, clear, and exact description thereof, reference being had to the accompanying drawings, and to the letters of reference marked thereon, which form a part of this specification.

This invention relates to a compromise or step rail-joint for joining the ends of rails of 15 different sizes or dimensions, of that class embracing a base-plate for supporting the meeting ends of the rails, a filling-plate which is interposed between one end of the base-plate and the superposed end of the smaller rail, 20 and which is made of proper thickness to compensate for the difference in height of the two rails and joint-bars which are clamped to the opposite sides of the rails and the end portions of which have their bearing-surfaces laterally and vertically offset to correspond with 25 the different dimensions of the rails.

The invention consists in the matters hereinafter described, and pointed out in the appended claims.

30 In the accompanying drawings, illustrating my invention, Figure 1 is a side view of a rail-joint embodying my invention. Fig. 2 is a plan view thereof with the central part thereof in horizontal section. Fig. 3 is a cross-section taken upon line 3 3 of Fig. 1. Fig. 4 is a cross-section taken upon line 4 4 of Fig. 1. Fig. 5 is a perspective view of the filling-plate.

As shown in the drawings, A A' indicate 40 the adjacent ends of two ordinary track-rails of different size or weight.

B indicates a base-plate on which the adjacent ends of the rails rest.

C indicates a filling-piece which is inserted 45 between the base-plate B and the end of the smaller rail A'.

D D' indicate inner and outer joint-bars which fit against opposite sides of the rail ends and are clamped thereto by means of 50 bolts E E'.

The said base-plate B is provided at its outer margin with a raised longitudinal rib B', which forms an inwardly-facing shoulder against which bears the outer edge of the base-flange of the larger rail A and also the outer edge 55 of the filling-plate C. Said filling-plate C, which rests upon the base-plate B with its outer margin in contact with the rib B', is provided at its outer margin with a raised longitudinal rib C', forming an inwardly-facing 60 shoulder adapted for contact with the outer margin of the base-flange of the smaller rail A'. The base-plate is spiked to the ties and held thereby from lateral outward movement. Shifting of the end of the larger rail 65 outward on the base-plate is prevented by contact of the base-flange of the rail with the rib B', while like outward shifting of the adjacent end of the smaller rail A' is prevented by contact of the base-flange thereof with the 70 rib C' of the filling-plate and by contact with the outer margin of said filling-plate with the rib B' on the base-plate.

In the particular construction shown in the drawings the base-plate B is longitudinally 75 corrugated in form for the purpose of giving stiffness thereto and to afford elevated bearing-surfaces to support the rail ends and intermediate grooves or depressions to receive sand, grit, or cinders, and thereby prevent re- 80 tention of the same between the base-plate and the rail ends and consequent wearing away of the parts. Said base-plate, as shown in the drawings, is provided with flat elevated relatively wide inner and outer marginal portions b b', which come beneath the side margins of the base-flanges of the rail and with an intermediate corrugated portion 85 forming a plurality of flat-top bearing-surfaces b² b², located in the same horizontal plane 90 with the upper surfaces of the marginal parts b b' and forming also flat bottom surfaces b³ b³, which bear on the top surface of the ties. Outside of the inner elevated part b the inner side margin of the base-plate is extended 95 downwardly and then horizontally outward to form an oblique part b⁴ and a horizontal marginal flange b⁵. The bottom surface of said horizontal flange b⁵ is in the same horizontal plane with the bearing-surfaces b³ b³ and is 100

adapted to also rest upon the ties. The rib B' is formed at the edge of the outer elevated marginal part b'.

In the construction shown the joint-bars D 5 D' have the form of angle-bars adapted to fit at their upper margins against the under surfaces of the rail-heads and at their lower margins against the top surfaces of the base flanges of the rail. The top and bottom bearing 10 or contact surfaces of said joint-bars D and D' at opposite sides of the said bars are offset vertically from each other, so as to correspond in position with the under surfaces of the rail-heads and the top surfaces of the base flanges of the rails A and A'. In the case of the 15 outer joint-bar D' the same is also offset laterally at its ends to correspond with the outer faces of the rails, as shown in Fig. 2. The inner joint-bar D is substantially straight to correspond with the inner side faces of the rail-heads, which are in alinement with each other.

In the form of joint illustrated the outer joint-bar D' has the form of an angle-plate and is provided at its lower margin with a 20 flange D², which extends outwardly over the base-flanges of the rail ends and downwardly outside of the side margins of said base-flanges and which terminates in an inwardly-extending horizontal flange d. Said horizontal 25 flange d is adapted to extend beneath the adjacent elevated marginal part b' of the base-plate. The lower surface of said horizontal flange d is, moreover, made flush with the bottom or bearing surfaces b³ b³ of the base-plate, so that said horizontal flange d, constituting the base of the joint-bar D', is adapted 30 to rest or bear upon the ties to which the base-plate is secured.

The base-plate B is shown as provided near 35 its inner margin with two spike-holes B² B², through which may be driven spikes that serve both to hold the base-plate from outward movement on the ties and also to confine the outer edges of the base-flanges of the 40 rails against the base-plate. The filling-plate C is provided in its inner edge with an aperture or notch c, adapted to receive the spike which passes through the spike-hole B² in the end of the base-plate on which the said filling-plate rests. Such holding-spikes when engaged with the notch c serve to hold the said filling-plate from sliding or shifting endwise on the base-plate, and thus getting out of its 45 position beneath the rail. The outer joint-plate D' is shown as provided at the outer margin of its flange D² with an outwardly-extending rib d', forming a horizontal extension of the flange d and provided with notches D³ D³ for engagement with spikes which serve 50 both to aid in holding parts, constituting the joint, against or in contact with the ties and to aid in holding the rails from outward movement on the ties.

A principal feature of my invention is em- 55 braced in the construction by which the base-

plate is provided with an inwardly-facing longitudinal shoulder against which laterally bears the base-flange of the larger rail and also the filling-plate and on which said filling-plate is provided with a like longitudinal inwardly-facing shoulder against which bears the outer margin of the base-flange of the smaller rail. The advantage gained by this construction is that the ends of the rails are thereby reliably and certainly held from lateral movement under the outward stress or pressure which comes thereon by the action of the car-wheels, it being understood that the rails are by the construction described positively held from outward movement on 75 the base-plate and that the latter is firmly spiked to the ties.

An important feature of the joint described is the notch or aperture in the filling-plate C, by which the latter may be engaged by one 80 of the holding-spikes, and thereby held in place on the base-plate or restrained from shifting from its position beneath the end of the smaller rail. In this connection it is to be noted that if the filling-plate be made wider 85 than illustrated the said notch or aperture in the filling-plate will be formed in the plate instead of at the edge thereof, the result in either case being that the filling-plate is held by the spike engaged therewith from endwise 90 movement and also from movement laterally away from the longitudinal shoulder of the base-plate. The said filling-plate C is shown as provided in its bottom surface with longitudinal grooves c' c', preferably spaced to 95 correspond with the grooves in the top of the base-plate B, so that the bearing-surfaces between said grooves c' c' will rest or bear on the elevated parts or ridges of the base-plate. The grooves c' c' serve to make the filling-plate 100 lighter in weight without lessening its efficiency as a support for the rail which rests thereon.

I claim as my invention—

1. The combination with rails of different 110 sizes, of a base-plate provided with a longitudinal inwardly-facing shoulder against which bears the base-flange of the larger rail, and a filling-plate resting on said base-plate in contact with said shoulder, said filling-plate being provided at its outer margin with a longitudinal, inwardly-facing shoulder against 115 which bears the base-flange of the smaller rail.

2. The combination with rails of different 120 sizes, of a base-plate provided with a longitudinal inwardly-facing shoulder, a filling-plate resting on said base-plate in contact with said shoulder, said filling-plate being provided with a longitudinal inwardly-facing shoulder, and a joint-plate provided with a flange which extends outwardly over the base-flanges of the rails, and having an inwardly-directed horizontal flange extending beneath the adjacent margin of the base-plate.

3. The combination with rails of different 125

sizes, of a base-plate provided at its outer edge with an elevated marginal part and with a longitudinal inwardly-facing shoulder, a filling-plate resting on said base-plate with its outer 5 margin in contact with said shoulder, said filling-plate being provided at its said outer margin with a longitudinal inwardly-facing shoulder, and a joint-plate provided with a flange which extends outwardly over the base-flanges 10 of the rails and having at its lower margin an inwardly-directed horizontal flange extending beneath the elevated marginal part of the base-plate.

4. The combination with rails of different 15 sizes, of a base-plate and a filling-plate resting on said base-plate beneath the smaller rail, said filling-plate being provided with an aperture for engagement with a spike.

5. The combination with rails of different 20 sizes, of a base-plate provided with a longitudinal inwardly-facing shoulder, and a filling-plate resting on said base-plate in contact with said shoulder and provided with a notch for engagement with a spike.

25 6. The combination with rails of different sizes, of a base-plate provided with a longitudinal inwardly-facing shoulder, and a filling-plate resting on said base-plate in contact with said shoulder and provided at its outer mar-

gin with a longitudinal inwardly-facing shoulder, and at its inner margin with an aperture 30 for engagement with a holding-spike.

7. The combination with rails of different 35 sizes, of a base-plate provided at its outer margin with a longitudinal, inwardly-facing shoulder, a filling-plate resting on said base-plate with its outer margin in contact with said shoulder, and provided at its outer margin with a longitudinal, inwardly-facing shoulder, said base-plate being provided near its inner 40 margin with spike-holes, and the filling-plate being provided in its inner margin with an aperture for engagement with a spike driven through one of said spike-holes.

8. The combination with rails of different 45 sizes, of a base-plate, and a filling-plate resting on said base-plate beneath the smaller rail, said filling-plate being longitudinally grooved on its bottom surface.

In testimony that I claim the foregoing as 50 my invention I affix my signature, in presence of two witnesses, this 2d day of March, A. D. 1905.

BENJAMIN WOLHAUPTER.
